DESIGN FOR A COMBINATION DESK UNIT

Albert S. Brand, Boston, and Laurence W. Kendrick, Wellesley, Mass., assignors to The Carter's Ink Company, Cambridge, Mass., a corporation of Massachusetts

Application June 11, 1938, Serial No. 77,784

Term of patent 7 years

To all whom it may concern:

Be it known that we, Albert S. Brand and Laurence W. Kendrick, citizens of the United States and residents, respectively, of Boston, in the county of Suffolk, State of Massachusetts, and of Wellesley, in the county of Norfolk, State of Massachusetts, have invented a new, original, and ornamental Design for a Combination Desk Unit, of which the following is a specification, reference being had to the accompanying drawing, forming part thereof.

Fig. 1 shows in perspective a combination desk unit showing our new design; and
Fig. 2 is a front elevation thereof.

We claim:

The ornamental design for a combination desk unit, substantially as shown.

ALBERT S. BRAND.
LAURENCE W. KENDRICK.
